UNITED STATES PATENT OFFICE.

RICHARD V. TODENWARTH, OF FULDA, GERMANY.

EXTINGUISHER FOR CANDLES.

SPECIFICATION forming part of Letters Patent No. 728,427, dated May 19, 1903.

Application filed August 25, 1902. Serial No. 120,943. (No model.)

To all whom it may concern:

Be it known that I, RICHARD VON TODENWARTH, merchant, a subject of the German Emperor, and a resident of 6 Wilhelmstrasse, 5 Fulda, in the German Empire, have invented new and useful Improvements in Extinguishers for Candles, of which the following is a specification.

This invention relates to an improved extinguisher for candles which offers the advantage that it acts not only automatically but extinguishes the candle thoroughly and in such a manner that the wick is not pressed down, as is the case with the extinguishers of 15 candles of known constructions.

In the accompanying drawings a candle-extinguisher according to my invention is shown in Figure 1 in a perspective view as fixed to a candle. Fig. 2 is a top view of the 20 extinguisher, and Fig. 3 is a vertical section on line A B of Fig. 2.

The improved candle-extinguisher consists of a tube *a*, which can be used as a socket for the candle. To the upper end of this tube *a* a plate *b* is attached, which has one end *c* bent upwardly. On the two long sides of the plate *b* projections *d e* are bent upward and then horizontally, so as to form ribs over which grip the folded edges of a plate *f*, 25 adapted to slide forward and backward on said ribs. To the lower surface of the plate *b* a laterally-projecting arm *g* is fixed, which carries a pin *h*, around which a spring *i* is coiled, which has a longitudinal arm *k*. On 30 the upper surface of the sliding plate *f* a pin *m* is fixed, which serves as an abutment for the arm *k* of the spring *i*.

The candle-extinguisher acts in the following manner: Before the tube *a* is placed over

the candle the sliding plate *f* is moved sideways, so that the opening of the tube *a* becomes free. Hereby the arm *k* of the spring *i* is moved backward by the pin *m*, so that it presses against this pin and presses the sliding plates *f* finally against the candle. As soon as the candle is burned down to the upper rim of the tube *a* the sliding plate being no longer held by the candle follows the pressure of the arm *k* of the spring *i* and is pushed over the candle along the guiding- 45 ribs *d e*, covering the candle, which is thus extinguished automatically.

Having fully described my invention, what I claim, and desire to secure by Letters Patent, is—

An improved extinguisher for candles comprising in combination with the tube or socket for the candle, a horizontal plate on the upper end of said tube prolonged at one end, lateral projections on the long sides of said plate bent upward and then horizontally to form guide-ribs, a sliding plate gripping with its folded edges over said guide-ribs, a laterally-projecting arm fixed to the lower surface of the tube-plate, a vertical pin on said arm, a spring coiled around said pin, a pin on the upper surface of the sliding plate serving as abutment for the free end of said spring, substantially as described and shown and for the purpose set forth.

In testimony whereof I have hereunto set my hand in presence of two subscribing witnesses.

R. V. TODENWARTH.
